UNITED STATES PATENT OFFICE.

JONES H. ROBERTS AND GUS ROLNICK, OF HOUSTON, TEXAS.

PROTECTOR FOR THE CROWN OF HEADWEAR.

1,139,803.

Specification of Letters Patent.

Patented May 18, 1915.

Application filed March 7, 1914. Serial No. 823,053.

To all whom it may concern:

Be it known that we, JONES H. ROBERTS and GUS ROLNICK, citizens of the United States, residing at Houston, in the county 5 of Harris and State of Texas, have invented certain new and useful Improvements in Protectors for the Crown of Headwear, of which the following is a specification.

This invention relates to new and useful 10 improvements in a protector for the crown of headwear.

The object of the invention is to provide a device of the character described designed to be inserted within the crown of hats and 15 caps, and particularly close fitting crowns, such as those of uniform caps, for the purpose of keeping the same out of contact with the head of the wearer, thus preventing the soiling of the crowns.

20 The device also serves to maintain the desired form of said crown, when applied to caps, or headwear formed of fabric or other pliable material.

A still further feature of the invention 25 resides in the provision of a device of the character described, which is adjustable so that it may be applied to crowns of different sizes, and which may be readily applied to and detached from said crown.

30 With the above and other objects in view, the invention has particular relation to certain novel features of construction, use and arrangement of parts, an example of which is given in this specification, and illustrated 35 in the accompanying drawings, wherein—

Figure 1 is a plan view of the complete device. Fig. 2 is a sectional side elevation thereof, as applied to a cap. Fig. 3 is a plan view of one of the supporting legs of 40 the frame. Fig. 4 is an edge view thereof. Fig. 5 is an edge view of a sliding sleeve employed. Fig. 6 is a plan view thereof, and Fig. 7 is an enlarged fragmentary sectional view of the circular disk employed in the 45 device, showing the method of attaching the radial ribs of the frame thereto.

Referring now more particularly to the drawings, wherein like reference characters 50 designate similar parts in each of the figures, C refers to a disk, which is formed of cork or some similar light material, which is plain on its underside and is preferably made concaved or hollowed out on its upper side, but which has a thick outside rim for the purpose 55 of stiffening the disk and giving suitable width for fastening the radial ribs J,

J, J, J. These ribs are formed of non-corrosive flat metal and are four in number. Their inner ends are inserted into the rim of the disk C, said inserted ends being indicated by the letters e. The ribs are then bent at right angles to said inserted ends and the wire band d is secured therearound passing entirely around the disk C. The said ribs are then again bent so as to bring their outer portions into alignment with said disk. 60

The letters l, l, l, l designate the supporting legs of the framework, whose upper ends are turned inwardly and connected to the respective ribs J, J, J, J, by means of slip joints b, b, b, b, as shown in Figs. 1, 5 and 6. Near the angle of each of the legs l on the inside is a hook, said hooks being designated by the letters g, g, g, g and these hooks support a circular flat spring a, said spring being fastened at the points m, m, m, m. The spring a is formed of flexible material and is open at k and is somewhat larger in diameter than the diameter of the largest sized hat or cap, so that the spring may be easily lessened in diameter by adjustment of the joints b, so as to fit a crown of any dimensions. The lower end of each of the legs l has on its outside a barb, said barbs being indicated by the letters f, f, f, f, which project into the stiffening i of the cap back of the sweat band h, thereby securely fastening the device in place. 70

The central disk C constitutes the chief feature of this invention, serving, as it does, to hold the top of the crown out of contact with the head and the frame shown for holding the same in place is of minor importance, as its mechanical construction can be readily varied in different ways to accomplish the desired result. However, as this device will be used chiefly in caps, the particular framework described will be found to be practical, not only for the purpose of holding said disk in place but also for the purpose of preserving the form of the crown. 90

While we have shown and described only one form of this device it is obvious that the mechanical form and arrangement thereof may be varied to suit different styles of headwear and we hereby reserve the right to make such mechanical alterations therein as will not depart from the scope of the appended claims. 95

What we claim is:—

1. A device of the character described including a disk, a plurality of ribs secured 100

110

thereto and radiating therefrom, a corresponding number of supporting legs whose upper ends are turned inwardly and united by means of slip joints to the respective ribs and a circular flexible member supported by said legs, said framework consisting of a plurality of radiating legs, adjustable lengthwise, and a circular, flexible member supported by the legs.

10 2. A device of the character described including a disk formed of light material, an adjustable framework adapted to fit within the crown of a hat or cap and hold said disk centered relative to the top of said crown, said framework including a plurality of ribs secured to said disk and radiating therefrom, a corresponding number of supporting legs whose upper ends are turned inwardly and adjustably secured to the respective ribs, each leg having a projecting barb which engages in the fabric of the crown and holds said device in place.

15 3. A device of the character described including a disk, formed of light material,

whose upper side is concaved, an adjustable frame work adapted to fit within the crown of a hat or cap and hold the said disk centered relative to the top of said crown, said frame work consisting of a plurality of radiating legs, adjustable lengthwise, and a 30 circular flexible member, supported by legs.

4. A device of the character described, including a disk, a plurality of ribs, secured thereto and radiating therefrom a corresponding number of supporting legs, whose 35 upper ends are turned inwardly and united by means of slip joints to the respective ribs and a circular flexible member supported by said legs.

In testimony whereof we have signed our 40 names to this specification in the presence of two subscribing witnesses.

JONES H. ROBERTS.
GUS ROLNICK.
